B. L. Greenough,

Making Carriage Wheels.

Patented Sep. 12, 1815.

Brackets & Greenough

2378X

Letters Patent

The Vehicle referred to in these Letters Patent and making part of the same containing a description in the words of the said 'Brackets & Greenough himself of his machine for facilitating the making of carriage wheels.

The particularities of which consists in making round holes on the outer ends of wagon and other carriage wheels spokes without the assistance of a spike or scoop, and bringing the shoulder of the spoke gradually from the centre of the nose and fitting them to the following. The bowls and pins likewise are made with the same machine.

The machine consists of a frame of suitable timber about four or five inches square and six feet long, two feet wide and two feet high is formed together at one end by means of two posts and two girts, and in the centre of the frame are two other girts, one in the bottom and the other on the top of the frame, one perpendicular over the other. Then the centre of which two girts are to be made two square mortises, one perpendicular over the other in which are fitted two square pieces of timber, each about one foot and a half long and about three inches square, and are mortised up and down but may be secured at will by two keys that press in contact with them, these are set in an opposite direction, the ends of these square pieces of timber that point toward each other in the centre are bevelled or nearly rounded and which constitute the pins, which confine the nose of the wheel (after the spikes are driven) while the tenons are cut on the ends, as will be known after described.

About a foot and a half or two feet square the head of the machine are two other girts placed in the same direction with the great girt, on the ends of which tenons are made which slide into a mortise made there the beams so that the girts may be moved to or from the centre of pins girts according to the length of the spokes or standards that have more than one two or three.

The standards are two pieces of timber that

join there a mortise made in the centre of the goads of an ordinary square
about six inches by one and a half inch. The end of the spoke to be cut
to a tenon is driven between them and confined by two keys that are
placed in the mortise each side. The standards in the top post. That
when one spoke is cut to a tenon the standards can be hoisted up by
loosening the wedges or keys and another spoke driven between them
at the end of the frame as the head post they best is framed in the
centre of the two goads. The stem in the same manner with the stan-
dard goads and more like them except they may be confined at any
place below. The standard goads and the end of the frame by open
joint (as that done in the ends of the tenons and when moreover
it skin with the tenon along the mortise. As the distance from the
head post to the posts that confine the same may be varied accord-
ing to the diameter of the wheel or the longitude of the spokes on which the
horses are to be cut - the frame is articulated to slide to and from the
cutter or press inwards upon a carriage of a suitable height to con-
vene the workmen. One end of the carriage is framed into the
posts that are nearly as high as the centre of the sliding post of the
machine when mounted on the carriage. Into these posts and
on a right angle with the machine are placed (horizontally)
two blocks of timber about four or five inches square and are placed
about a foot apart. and may be long enough on which to hang
a wheel for the purpose of turning the beam man driller if you
intend to operate by hand. If by water they may be no longer than
a six inch is needed. Upon these and on a line with the centre of
the sliding post of the machine are placed the two blocks to which the beam
man driller may be made of a hand that passes round a wheel on
the post of it. When the man driller is placed on these it must
freight there the centre of the head post but is prevented from go-
ing too far by a shoulder on the inner side (inside of the hollow post)
that when the tenon is fast as the shoulder is cut away by the teeth
in the end of the cylinder. The frame is moved on the carriage up
to the machine by means of a small piece of timber that is framed

on at the foot of the head post and passes horizontally this distance under the mandrill, the opposite end of which is formed into a shoulder and of which is formed onto a collar that turns in a spoke at the head of the machine and gives a sufficient purchase by which the frame is easily moved up to the cutter till stopped by the shoulder on the head post against the shoulder on the mandrill back of the cylinder. so that by moving the head post you may bring the cutter up to the bar and cut the tenon. In longer ones or for wheels of greater diameter the head post must be moved nearer the head of the machine. so likewise must be moved the standards and guides to bring the standards a suitable distance from the end of the spoke —

The Burre mandrill is made of iron about 2 foot and a half long. The bar on the cutting end of it is a cylinder about an inch longer than the tenon, intended to be cut which the cylinder receives, about an inch of the end of the cylinder is steel, three eighths of an inch thick, being twice the thickness of the cylinder from the cutting end to the shoulder or guides. This shoulder is somewhat larger than the cutting end and when the head block is suitably placed prevents the sliding part of the machine from moving too near the cutter, and comes to a shoulder in the post when the tenon is cut down. The cutting end of the cylinder has one or more teeth that cut away the shoulder while the tenon is received into it — The down and planing is likewise made by presenting the — the bar of a suitable size to the Burre.

After the spokes are set in the nave, the nave is placed upon the post, and keyed to it, so that the end of the spoke points directly to the Burre. a spoke is then made fast between the standards the Burre set in motion the workman by means of the lever draws up the machine till the tenon is cut on the end of the end of the spoke. The machine is then thrown back by the same means which draws the tenon out of the cylinder of the bar and now the standards are to be removed and the operation repeated till all are cut. Of course, may require this machine with very

little attention may stand perpendicular, between posts in this case the left of the sliding part would apply sufficient force to the man, while and nearly the same man might be employed in using it, as in this case
